VARIABLE SPACING MECHANISM FOR TYPEWRITERS

Filed March 30, 1943

5 Sheets-Sheet 5

A technical line drawing of a mechanical assembly. The drawing shows a central horizontal rod with various parts attached. On the left, a vertical plate labeled '10' has a slot and a pin labeled '12'. A horizontal plate labeled '12' is attached to the right of the slot. A central assembly includes a pin labeled '20', a slot labeled '21', a pin labeled '22', a pin labeled '23', a pin labeled '24', a pin labeled '25', and a pin labeled '26'. A pin labeled '40' is attached to the right side of the central assembly. A pin labeled '41' is attached to the left side. A pin labeled '51' is attached to the bottom left. A pin labeled '55' is attached to the bottom right. A pin labeled '22' is attached to the bottom center. The drawing uses hatching and cross-hatching to distinguish different parts.

VARIABLE SPACING MECHANISM FOR
TYPEWRITERS

James L. Webb, Gainesville, Tex.

Application March 30, 1943, Serial No. 481,130

10 Claims. (Cl. 197—84)

This invention relates to a variable spacing mechanism for typewriters, and it is an object of the invention to provide a mechanism of this kind wherein the mechanism is under control of a universal spacing bar which is automatically raised and lowered in its spacing position by the mechanism which shifts the typewriter carriage for printing lower case letters and capital letters.

It is also an object of the invention to provide a mechanism of this kind including a universal spacing bar which is moved varying distances as determined by the pressure of the varying contours of the heels of the type bars as such type bars are thrown into printing position by the operator striking the keys of the typewriter.

An additional object of the invention is to provide a mechanism by means of which the carriage or platen of a typewriter will move varying distances as the keys and type bars are operated according to the sizes of the letters or characters printed instead of moving the platen always a fixed distance as is done in typewriters now generally in use.

The invention consists in the details of construction and in the combination and arrangement of the several parts of my improved variable spacing mechanism for typewriters whereby certain important advantages are attained, as will be hereinafter more fully set forth.

In order that my invention may be better understood, I will now proceed to describe the same with reference to the accompanying drawings, wherein:

Figure 1 is a fragmentary view in top plan illustrating a mechanism constructed in accordance with an embodiment of the invention.

Figure 2 is a view in rear elevation of the structure as illustrated in Figure 1.

Figure 3 is a sectional view taken substantially on the line 3—3 of Figure 2, looking in the direction of the arrows and showing the parts in the upper case shift position.

Figure 4 is a detailed sectional view taken substantially on the line 4—4 of Figure 3, looking in the direction of the arrows.

Figure 5 is a fragmentary view in rear elevation, with portions broken away, showing in detail certain details of construction.

Figure 6 is a sectional view taken substantially on the line 6—6 of Figure 5, looking in the direction of the arrows.

Figure 7 is a detailed sectional view, with parts in plan, the section being also substantially on the line 6—6 of Figure 5.

Figure 8 is a view of the universal spacing bar, unapplied.

Figure 9 is a fragmentary detail view, partly in elevation and partly in section, showing the heel portion of a type bar.

Figure 10 is a view in elevation of the segment block as comprised in the structure of the typewriter, said block being unapplied, and

Figure 11 is a view in perspective illustrating another embodiment of the invention.

As disclosed in the accompanying drawings, B denotes a type bar bearing or segment block as comprised in the structure of typewriters now well known in use and which has its lower 15 arcuate marginal portion provided with properly spaced slots 1 in each of which is received the heel portion 2 of a type bar 3. Each of these type bars 3 is pivotally connected with a pivot rod 4 arranged within a channel 5 in the lower 20 arcuate marginal portion of the bearing or block B and concentric to the lower arcuate edge of said bearing or block B.

This channel 5, as clearly illustrated in Figure 10, intersects the slots 1 adjacent the outer ends 25 thereof, while intersecting the rear portions of the slot 1 is a second channel 6 provided in the bearing or block B and which channel is concentric to the channel 5. This channel 6 is of a material width to allow the universal spacing bar 30 7 therein to be raised or lowered in its spacing position by the usual mechanism which shifts the typewriter carriage for printing lower case letters and capital letters.

This bar 7 is also adapted to be shifted laterally 35 when in either its raised or lowered position a distance determined by the rounded upper edges 8 and 9 of the heel portion 2 of the type bar 3 as the bar 3 rises to printing position. The edge 8 is effective when the bar 7 is in its lowered position and the edge 9 is effective when the bar 7 is in its raised position.

The bar 7 at desired points inwardly of its ends has rigid therewith the rearwardly disposed elongated arms 10, the outer or free end portions 45 of which are pivotally connected, as at 11, with the outstanding arms 12 carried by and at the opposite sides of the flat frame 14. The inner or forward end of this frame 14 at a desired point intermediate its ends is provided with the outstanding and coplanar flat extension arm 15 which enters the properly positioned slot 16 in the bearing or segment block B. This arm 15 coacts with the block B to hold the frame 14 in perfect alignment.

55 The escapement mechanism proper comprises

a main plate 17 provided at its top and to one side thereof with a single cog stop 18 which coacts with the conventional star wheel 19 which controls the lateral motion of the typewriter carriage. This plate 17 is supported for pivotal movement about a horizontal axis in the main frame 20 of the escapement mechanism by the pins 21 having direct coaction with the outstanding lugs 22 carried by the plate 17. This mounting of the plate 17 allows the upper portion thereof to have fore and aft swinging movement for a purpose to be hereinafter more particularly referred to.

The upper portion of the plate 17 in its central part has secured thereto, as at 23, a guide block 24 which is freely disposed through an elongated slot 25 disposed longitudinally of a slide member or plate 26 having close contact with the upper portion of the outer surface of the plate 17. This block 24 has its outer longitudinal margins defined by the outstanding flanges 27 for coaction with the outer face of the applied plate 26 and thus provide means for holding said plate in applied or working position yet permitting the same to freely move lengthwise. The plate 26 at the end portion thereof adjacent to the cog stop 18 is provided with the upstanding stop finger 28 for coaction with the star wheel 19, as will later be pointed out.

The lower portion of the plate 26 remote from the cog stop 18 and the stop finger 28 is cut away to provide the stepped shoulders herein disclosed as three in number and identified by the numerals 29, 30 and 31. These shoulders 29, 30 and 31 are, of course, spaced lengthwise of the plate 26 along the lower margin thereof, with the outer shoulder innermost.

Selectively engageable with these shoulders 29, 30 and 31 is the inwardly and laterally disposed flat lug 32 carried by and coplanar with the upper portion of the flat stop plate 33 positioned adjacent the outer face of the plate 17 and free for movement in a vertical direction. The side edges of this movable plate 33 are straight and in parallelism, the outer edge 34 coacting with the adjacent lug 22 of the plate 17 while the inner edge 35 has contact with an outstanding pin 36 carried by the plate 17 at a point in relatively close proximity to the applied plate 26.

The pin 36 and the lug 22 between which the plate 33 is positioned and travels serve to maintain the plate 33 in its effective position so that the same can have the desired up and down movement. This plate 33 is constantly urged upwardly by the retractile member 37, herein shown as a coiled spring, having one end portion suitably anchored, as at 38, to the movable plate 33 and its opposite end portion suitably connected, as at 39, to the lug 22 which provides a guide for said plate 33.

The plate 26 is constantly urged toward the plate 33 by the retractile member 40, also herein disclosed as a coiled spring, having one end portion suitably anchored to an outstanding lug 41 carried by the lower portion of the plate 26 adjacent to the end thereof remote from the plate 33. The opposite end portion of this retractile member 40 is suitably secured to an outstanding lug 42 carried by the plate 17 at a desired point above the adjacent lug 22.

Pivots connected, as at 43, to the lower portion of the plate 33 is an extremity of a substantially horizontally disposed rock arm 44 having its central portion pivotally connected, as at 45, to a depending flat lug 46 carried by the plate

17. The free end portion of this arm 44, or that end portion remote from the pivotal connection 43, overlies and is positioned in constant contact with a forwardly disposed short arm 47. This arm 47 is arcuate in form, as particularly illustrated in Figure 3, and is forwardly and upwardly disposed and has its lower end portion suitably anchored, as at 48, to an arm 49 depending from the lower cross arm 50 of the rocker frame 51. As clearly illustrated in Figure 3, this arm 47 is flat and has its upper free end portion formed to provide a relatively long and slightly inbow contacting edge 52 with which the rock arm 44 directly contacts. The cross member 50 of this rocker frame 51 is held between the pins 53 carried by the main frame 20, or more particularly the outstanding brackets 54 carried by said main frame at a desired point below the plate 17.

The upper cross member 55 of the rocker frame 51 extends outwardly beyond the opposite sides thereof and has pivotally connected therewith the outer or free end portions of the arms 12 carried by the flat frame 14, so that as the frame 14 is moved or swung fore and aft, the upper portion of the rocker frame 51 will be correspondingly rocked or oscillated and the extent of this movement of the frame 14 will be determined by the throw of an edge 8 or 9 of the type bar 3 as it swings to strike or print.

When the operator strikes the required type key to operate the type bar 3 to throw the type bar up to printing position, the heel 2 of the type bar 3 makes a thrust with one of its edges 8 or 9 against the universal spacing bar 7 and this thrust is conveyed through the arms 10 to the flat frame 14 and through the arms 12 to the rocker frame 51, moving it backward, of course, according to the length of the thrust of either of the edges 8 or 9.

During this backward movement of the rocker frame 51, the short arm 47 swings upwardly against the adjacent end portion of the arm 44, resulting in downward movement of the stop plate 33. As this plate 33 passes below a shoulder 29 or 30, the spring 40 will sharply move to the right the sliding plate 26. It is believed to be obvious that the extent of such movement of the plate 26 will be dependent upon the extent of downward movement of the stop plate 33 as determined by the length of the thrust of an edge 8 or 9 upon the spacing bar 7. The extent of movement of this plate 26 determines the width of spacing according to the size of character to be printed and all of this is accomplished on the up-stroke of the type bar 3.

The completion of the spacing movement is accomplished on the back stroke, as the type bar 3 falls back to normal position and releases the pressure of its heel on an edge 8 or 9 against the universal spacing bar 7, thus allowing the spring 56 to return the flat frame 14 and the spacing bar 7, together with the rocker frame 51, to their normal positions. This spring 56 is herein disclosed as a coiled spring having one end portion anchored, as at 57, to the outer part of the frame 14 and the opposite end portion of the spring secured, as at 58, to the lower rear portion of the bearing or segment block B. As particularly illustrated in Figure 3 of the drawings, this spring 56 underlies the flat frame 14.

In this return or back stroke of the rocker frame 51, flat frame 14 and universal spacing bar 7, the collar 59 or other enlargement on the upper bar 55 of the rocker frame 51 presses

against the plate 26 and forces the stop finger 28 carried thereby to engage a tooth of the star or escapement wheel 19 and at the same time pushes the cog stop 18 at the top of the main plate 17 out of mesh with the star or escapement wheel 19. When this cog stop 18 is freed from the star or escapement wheel 19, the pull of the carriage return spring (not shown) rotates in a well known manner the star or escapement wheel 19, carrying the movable slide 26 forward or to the left until it strikes the beveled stop 60 suitably positioned on the main frame 20. As illustrated in the accompanying drawings, the left end portion of the plate 26 is provided with an upstanding lug or part 61 which has direct contact with the beveled stop 60. The force of contact of the lug or part 61 with the beveled stop 60 forces the stop finger 28 out of mesh with the star or escapement wheel 19 and brings the cog stop 18 back into mesh with the star or escapement wheel 19, thus completing the spacing movement and holding the typewriter carriage in place until another type bar key is struck.

It is believed to be obvious that the distance the typewriter carriage moves laterally when a letter is printed is controlled by the length of the thrust of an edge 8 or 9 against the universal spacing bar 7 and by having the two edges 8 or 9 on the heel of each type bar and by shifting the spacing bar 7 up or down, two spacing distances may be made on the same type bar, as for a lower case letter and for the capital of the same letter.

It is again pointed out that these varying thrusts are transmitted through the flat frame 14 and the rocker frame 51 to the escapement mechanism, releasing one, two or three teeth of the star wheel. It is also to be stated that the normal position of the plate 17 of the escapement mechanism is with the cog stop 18 in mesh with the star wheel 19. The movable or slide plate 26 normally stands in its extremely left position free of the star wheel 19 and held in such position by the stop plate 33 and being pulled up behind the last step or shoulder 29 by the spring 40. These several parts return to these positions after each spacing movement is completed.

The usual shifting bar 62 which supports the typewriter carriage and is connected in the usual manner (not shown) with the shift keys on the keyboard, is provided, at spaced points therealong and outwardly of the arms 10, with the rearwardly disposed lugs 63 with which are pivotally connected the upper end portions of the substantially vertical bars 64 each of which has its lower end portion pivotally connected, as at 65, with a rearwardly disposed rock arm 66 carried by the rock shaft 67. This rock shaft 67 underlies the flat frame 14 and is rotatably supported by the upstanding arms 68 carried by the bracket plate 69 suitably anchored to the usual frame cross member comprised in the typewriter construction.

When the shifting bar 62 is raised by the operator depressing a shift key on the keyboard, it automatically lowers the universal spacing bar 7 in its channel 6 through the medium of the additional vertically disposed bars 70 each pivotally connected, as at 71, at its lower extremity with a forwardly directed rock arm 72 carried by the rock shaft 67, and at its upper extremity each of said bars 70 is pivotally connected, as at 73, to the inner portion of an arm 10 of the universal spacing bar 7.

In the embodiment of the invention illustrated in Figure 11, the general construction and operation are substantially the same as has heretofore been set forth in connection with the first embodiment, but in lieu of the thrust edges 8 and 9 in the first embodiment of the invention, the universal spacing bar has coacting therewith a vertically disposed link bar 75 for making the desired thrust against the spacing bar 74. In this embodiment of the invention, this bar 75 is provided with two projecting steps 76 for selective contact with the adjacent edge of the bar 74, depending upon whether said bar 74 is at either its raised or lowered position.

15 The vertical bar 75 is connected to a key bar 79. The universal space bar 74, is connected to the shift key bar, not shown, by the links 80.

The vertical member or bar 75 of each type bar assembly, swings on the fixed cross rod 81 and is attached at its lower end by the obliquely directed link 83 to a key bar 79 as illustrated. When a key bar is struck, a down pull will be applied to the link 83, tending to straighten the link and thus effecting the oscillation or swinging 20 of the bar 75 on the rod 81, swinging the upper end of the rod 75 rearward. By this means a pull is applied to the link 77 which connects the upper end of the bar 75 with the type bar 18, causing the type bar to swing into printing position. In 25 this motion the bar 75 also makes a thrust against the universal space bar 74. If the shift key, not shown, with which the universal space bar 74 is connected, is depressed, the shoulder 76 of the bar 75 makes a longer stroke of the universal bar 30 74. When the shift key, not shown, is not depressed, the lower step of bar member 75 strikes the universal bar, making a shorter thrust or stroke. Thus each key on the keyboard is capable of making two distinct space thrusts. The bar 35 75 has, of course, to be individualized for each letter since some letters require the same space for both upper and lower case characters, as the figure "4" and the dollar sign (\$) on the same key, while other letters require triple variation 40 as the lower case "l" and the capital "L."

45 From the foregoing description it is thought to be obvious that a variable spacing mechanism for typewriters constructed in accordance with my invention is particularly well adapted for use by reason of the convenience and facility with which it may be assembled and operated.

What is claimed is:

1. A variable spacing mechanism for a typewriting machine having an escapement wheel for the movable carriage, a member supported for backward and forward movement transversely of the carriage, a spacing bar supported in position to be contacted by a type bar as the type bar swings into striking position for shifting the spacing bar in one direction, an operative connection between the spacing bar and the said member for movement one with the other, a vertically disposed rocker frame operatively connected with the member for movement therewith, a vertically disposed plate supported for swinging movement toward and from the escapement wheel, a cog stop carried by said plate for engagement with the escapement wheel, a plate movable transversely of the swinging plate, a stop finger carried thereby for engagement with the escapement wheel, means for constantly urging said movable plate in one direction across the swinging plate, a stop plate carried by the swinging plate, and means operated by the rocker frame for shifting the stop plate a distance determined by the

extent of swinging movement of the vertically disposed plate, said movable plate on the swinging plate having stepped shoulders with which the stop plate selectively engages as the stop plate is moved in a direction away from said movable plate.

2. A variable spacing mechanism as set forth in claim 1, further including means for constantly urging the member, spacing bar and the swinging plate forwardly.

3. In a typewriting machine having a carriage-actuated rotatable escapement wheel and type bars pivotally supported for swinging movement, means for effecting variable movement of the carriage in accordance with different widths of characters carried by the bars comprising heels of different contours on the type bars and bearing definite relations to the widths of the characters carried by the bars, a spacing bar supported to be actuated by the heels of the type bars on movement of the bars in printing, said spacing bar being actuated to decrease by the different contour forms of the heels, a vertically disposed swinging plate positioned adjacent to the escapement wheel, a stop cog carried by the plate engageable with the escapement wheel, a plate supported for sliding movement transversely of the swinging plate, a stop finger carried by the sliding plate for engagement with the escapement wheel, the stop finger engaging the escapement wheel when the stop cog is free of the escapement wheel and vice versa, and means for automatically moving the sliding plate when the stop finger thereof is in engagement with the escapement wheel a distance determined by the extent of movement imposed on the spacing bar as a type bar swings for printing.

4. A spacing mechanism as set forth in claim 1, wherein the means for shifting the stop plate comprises a rock arm carried by the swinging plate and operatively connected with the stop plate, a swinging frame operating upon movement of the spacing bar, an arm carried by said last frame and engaging the rock arm upon swinging of the frame in one direction to move the stop plate away from the sliding plate, and means for constantly urging the stop plate toward the moving plate.

5. In a typewriting machine having a carriage-actuated rotatable escapement wheel and type bars pivotally supported for swinging movement, means for effecting the variable movement of the carriage in accordance with different widths of the characters carried by the bars comprising heels of differing contours on the type bars and bearing definite relations to the widths of said characters, a universal spacing bar with which the heels of the type bars engage when the bars swing to typing position, said contours of the heels imparting movement to the universal spacing bar, a supporting structure positioned adjacent to the escapement wheel, a swinging plate mounted on said supporting structure and having a stop cog engageable with the escapement wheel, a plate mounted for sliding movement transversely of the swinging plate and having a stop finger engageable with the escapement wheel, means for constantly urging the sliding plate in one direction to oppose rotation of the escapement wheel when the stop finger of the sliding plate is in engagement therewith and the stop cog of the swinging plate is free of the escapement wheel, a shiftable stop member carried by the swinging plate for selectively controlling the extent of such movement of the sliding plate, a

frame pivotally mounted on the supporting structure, an operative connection between the universal spacing bar and said frame for swinging the frame in one direction upon movement of the spacing bar by contact therewith of a contour of the heel of a type bar, and coacting means carried by the frame and the stop member for moving the stop member a distance determined by the extent of movement of the spacing bar to permit the sliding plate to have selected movement.

6. A spacing mechanism as set forth in claim 5, wherein the means for swinging the frame comprises arms pivotally connecting the spacing bar and the first frame.

7. A spacing mechanism as set forth in claim 5, wherein the means for swinging the frame comprises arms pivotally connecting the spacing bar and the first frame, a swinging frame positioned adjacent to the swinging plate and connected to the spacing bar for movement therewith, said swinging frame having a part for contact with the swinging plate upon movement of the frame in one direction to cause the swinging plate to move in unison with the frame, and automatic means for moving the frame in such direction.

8. The combination with a typewriting machine including a bearing block, an upstanding supporting structure rearwardly of and spaced

30 from the block, and type bars pivotally supported by the bearing block for swinging movement; of means for effecting variable movements of the carriage in accordance with different widths of characters carried by the bars comprising heels of different contours on the type bars and bearing

35 definite relations to the widths of said characters, a universal spacing bar positioned adjacent to the bearing block for engagement by said heels on movement of the bars for printing, rear-

40 wardly disposed arms carried by the spacing bar, outstanding arms carried by the frame at the end thereof remote from the bearing block, the first named arms being pivotally connected with said second arms, a forwardly disposed part carried

45 by said frame slidably engaging within the bearing block, a carriage-operated escapement wheel carried by the supporting structure, a swinging plate mounted on said supporting structure and having a stop cog to engage the escapement

50 wheel upon movement of said swinging plate in one direction, a sliding plate carried by the swinging plate having a stop finger for engagement with the escapement wheel upon movement of the swinging plate in the opposite direction,

55 a vertically disposed swinging frame carried by the supporting structure and with which the arms of the first frame are operatively engaged for swinging said second frame in unison with the movement of the first frame, means operated upon movement of the swinging plate in one direction to allow the sliding plate to move a selected distance in one direction, and means under control of the spacing bar as moved by contact of a contour of a heel therewith for determining the selected distance of travel of the sliding plate.

9. In a variable shift mechanism for a typewriter having a toothed escapement wheel for a movable platen carrying carriage, a spacing bar supported for reciprocal movement, a swinging type bar having a heel and mounted for engagement of the heel with the spacing bar when the type bar is swung for a typing stroke, an oscillatably supported plate having an edge movable across the periphery of wheel,

two wheel engaging stops supported by the plate adjacent said edge for alternate engagement with the teeth of the wheel, one of said stops being movable toward and away from the other stop, the said other stop being normally in holding connection with a tooth of the wheel, movable means operatively coupled with the spacing bar to be moved thereby and for effecting a predetermined shifting of the said one stop away from the other stop for regulating the extent of movement of the carriage, means for disengaging the said other stop from and engaging the said one stop with a tooth of the wheel upon release of the shift bar by the type bar heel, and means for reengaging the said other stop with and disengaging the said one stop from a tooth of the

wheel after the wheel movement has been stopped by the said one stop.

10. A variable shift mechanism for a typewriter as set forth in claim 9, in which said type bar heel has two dissimilar portions for selective engagement with the spacing bar, the said spacing bar having up and down movement for selective engagement with the portions of a type bar heel, means for raising and lowering the spacing bar, the extent of movement of the said movable means and the degree of shifting the said one stop away from the other stop being determined by the character of the heel portion engaged against the spacing bar.

JAMES L. WEBB.
